UNITED STATES PATENT OFFICE.

GILES H. GRISWOLD AND SAMUEL GRISWOLD, OF TENNESSEE, ILLINOIS.

FENCE-POST.

1,098,252.

Specification of Letters Patent. Patented May 26, 1914.

Application filed March 5, 1912. Serial No. 631,717.

To all whom it may concern:

Be it known that we, GILES H. GRISWOLD and SAMUEL GRISWOLD, citizens of the United States, residing at Tennessee, in the 5 county of McDonough and State of Illinois, have invented new and useful Improvements in Fence-Posts, of which the following is a specification.

This invention relates to fence posts.

10 The object of the invention is to provide a simple, efficient and strong structure of this character with a minimum amount of material which may be cheaply manufactured and sold.

15 A further object of the invention is the provision of a substantially conical metallic post having an apertured flange running longitudinally of the same and adapted to receive the wires of the fence or securing 20 members for holding the wire to the post.

A still further object of the invention is the provision of a conical post having a detachable retaining flange which can be slipped over the post and which will bind 25 upon the post at its lower or large end, which flange is adapted to hold the post in the ground against the strain of the fence wires.

30 A still further object of the invention is the provision of a metallic post of this character having a longitudinal flange with novel means for securing the fence wires to the flange.

35 Further objects of this invention will appear as the following specific description is read in connection with the accompanying drawing, which forms a part of this application, and in which:—

40 Figure 1 is a side elevation. Fig. 2 is a horizontal section therethrough. Fig. 3 is a similar section showing the retaining flange applied thereto. Fig. 4 is a detail front elevation showing a modified form of flange before and after the wire has been applied 45 thereto. Fig. 5 is a detail side elevation of the structure shown in Fig. 4.

In the specific embodiment of the invention as illustrated herein, 1 represents a 50 sheet of metal whose free longitudinal edges are bent at an angle and disposed in a downwardly and outwardly inclined direction with respect to the sheet, to produce flanges 2 and 3, which when brought together to produce what will be hereinafter known as 55 the conical body 4, directly abut each other

throughout their length and form a wire receiving or securing flange hereinafter spoken of as the unitary member. The flange 2 is considerably longer or wider than the flange 3 and embraces and engages the longitudinal 60 edge of the latter mentioned flange and is thence bent and engaged with the full transverse width and longitudinal extent of the said shorter flange 3, for holding the flanges together in the form of a single retaining 65 flange. It is to be further stated that the free longitudinal edge of the longer flange 2 is thence engaged with the conical body member 4 throughout its entire longitudinal extent whereby affording a substantial 70 reinforcing member or brace for the post throughout its entire length. This retaining flange is provided with a plurality of apertures 5 which are either adapted to receive directly the fence wires or to receive securing devices which hold the wire to the post. 75

In Fig. 3, there is shown a retaining flange 6 which is centrally apertured as shown at 7 and has extending radially therefrom a slot 8 which opens into the aperture and is adapted to receive the wire retaining flange of the post. The central aperture 7 in the flange or disk 6 is of such size that the disk may be slipped down over the post until the walls of the aperture 7 frictionally bind 80 against the large or lower end of the post, and the outer side faces of its flanges 2 and 3. When the post is embedded in the ground with this flange in position upon the same, it will be readily perceived that the same is 85 held more firmly against any lifting strain produced by the wires where the same are stretched taut between two higher posts on opposite sides of the post having the flange.

In the modification shown in Figs. 4 and 90 5, the wire supporting flange is provided with splits or cuts 9 which extend into the wire receiving apertures 10. The portions between the apertures are bent as shown in Fig. 4 so as to permit the insertions of the 95 wires into the apertures 10, after which the portions between the apertures are bent into alinement, as is also shown in this figure. By this method, the wires do not have to be inserted through the holes and yet require 100 105 no additional or auxiliary fastening devices.

What we claim as new is:—

A fence post comprising an integral tubular conical body, a flange formed from the body and extending radially therefrom 110

throughout the entire length of the body, a removable flat retaining member apertured to surround the body, and the apertures thereof having extended radially therefrom an elongated slot, the apertures of said retaining member closely fitting the large end of the body and the elongated radial slot thereof frictionally engaging the radial flange formed from the body, whereby pre-

venting any accidental movement of the flange with respect to the body.

In testimony whereof we affix our signatures in presence of two witnesses.

GILES H. GRISWOLD.
SAMUEL GRISWOLD.
